[57] CLAIM

The ornamental design for a chair frame, as shown and described.

DESCRIPTION

FIG. 1 is a front perspective view of a chair frame showing my new design;

FIG. 2 is a left side elevational view, the right side being a mirror image thereof;

FIG. 3 is a front elevational view;

FIG. 4 is a rear elevational view;

FIG. 5 is a top plan view; and,

FIG. 6 is a bottom plan view thereof.

The broken line showing of cushions in FIGS. 2-5 is for environmental purposes only, and forms no part of the claimed design.

The weave pattern schematically shown on the chair frame in FIG. 1 is continuous throughout.

FIGS. 5 and 6 have been drawn to a smaller scale with respect to FIGS. 1 through 4.
